HEAT EXCHANGER APPARATUS

Wallace D. Canterbury, Gardena, Calif., assignor to
U.S. Industries, Inc., a corporation of Delaware

Application February 4, 1957, Serial No. 637,985

19 Claims. (Cl. 257—202)

The present invention relates generally to heat exchangers and more particularly to heat exchanger apparatus utilizing air as a medium for changing the temperature of a liquid.

In the United States Letters Patent No. 2,279,941, issued January 10, 1956, to H. E. Rose et al., there is shown a fluid actuated pumping jack which is especially adapted for use in pumping oil from an oil well. This fluid actuated pumping jack employs a vertically extending hydraulic cylinder and a piston slidably disposed therein. The piston is attached to the upper end of a sucker rod string, and it is raised in the cylinder by pressurized hydraulic liquid. A reservoir tank is provided for this hydraulic liquid, the liquid being pumped by a rotary pump from the reservoir tank to the lower end of the cylinder below the piston during a power stroke of the latter's piston. The hydraulic liquid is returned to the reservoir tank during the downward movement of the piston under the weight of the sucker rod string. During operation of this pumping jack, the temperature of the hydraulic liquid is often raised to the point that cavitation takes place within the rotary pump. Such cavitation not only reduces the efficiency of the unit but also results in extremely noisy operation. This noisy operation prohibits the use of these hydraulic pumping jack units near residential areas. The preferred form of heat exchanger apparatus embodying the present invention was especially adapted for use with the aforescribed pumping jack and when employed therewith is capable of maintaining the temperature of the hydraulic liquid sufficiently low that cavitation of the rotary pump does not occur.

It is a major object of the present invention to provide novel and improved heat exchanger apparatus.

Another object is to provide heat exchanger apparatus that utilizes high velocity air as a temperature-changing medium for a liquid, it having been determined that the rate at which an exchange of heat through a wall takes place is a function of the velocity of the fluids disposed on either side of the wall.

A further object of the invention is to provide heat exchanger apparatus that is compact in size and light in weight.

Yet another object of the invention is to provide heat exchanger apparatus of the aforescribed nature which is inexpensive to construct and maintain as compared to heretofore-proposed heat exchangers.

It is a further object of the invention to provide heat exchanger apparatus which is extremely efficient in operation whereby it affords a maximum temperature changing capacity with a minimum consumption of power.

An additional object is to provide heat exchanger apparatus especially adapted for use with a liquid-containing tank and wherein high velocity air is forced through the interior of this tank and thereafter is expelled over the tank's exterior.

Another object is to provide heat exchanger apparatus

incorporating a liquid-containing tank and a belt-driven blower, the blower being slidably mounted relative to the tank whereby the belt tightness can be controlled and the static head provided by the blower may be adjusted.

5 An additional object of the invention is to provide heat exchanger apparatus which is normally employed in cooling a liquid but which can readily be adapted to heat a liquid.

These and other objects and advantages of the present 10 invention will become apparent from the following detailed description, when taken in conjunction with the appended drawings wherein:

Figure 1 is a perspective view of a preferred form of 15 heat exchanger apparatus embodying the present invention;

Figure 2 is a fragmentary side elevational view of the 20 blower end of said apparatus;

Figure 3 is a vertical sectional view taken on line 3—3 of Figure 2;

25 Figure 4 is a vertical sectional view taken on line 4—4 of Figure 3;

Figure 5 is a horizontal sectional view taken on line 5—5 of Figure 4;

Figure 6 is a vertical sectional view taken on line 6—6 of Figure 4;

Figure 7 is a perspective view of a modified form of 30 said heat exchanger apparatus; and

Figure 8 is a fragmentary side elevational view of said modified form.

35 Referring to the drawings and particularly Figures 1 through 6 thereof, the preferred form of heat exchanger apparatus embodying the present invention includes a reservoir tank T for a quantity of hydraulic liquid 10, an air blower B mounted at one end of the reservoir tank T and having its discharge connected to main duct means M extending through the interior of the tank T. The ends of the main duct means M opposite the blower B are in communication with return duct means R. A conventional pump P is mounted upon the reservoir tank

40 T. This pump P and the blower B are driven by an electric motor E, the latter also being mounted upon the tank T. In operation, the pump P will draw hydraulic liquid 10 from within the reservoir tank T and pump it under pressure to a hydraulic unit (not shown), such as

45 a pumping jack or the like. The discharge of the pump P is connected to a pressure line 12 shown in Figure 1. The hydraulic liquid 10 will be withdrawn from the interior of the reservoir tank T through an inlet conduit 14, the upper end of which is connected to the intake of

50 the pump P. The hydraulic liquid will be returned to the interior of the reservoir tank T by a return line 16. The returned hydraulic liquid flowing through the reservoir tank T will be cooled by air forced through the main duct means M and the return duct means R by the blower B. The return duct means R are curved so as to direct the air which has passed through the main duct means M over the exterior of the tank T.

More particularly, the reservoir tank T is generally cylindrical in configuration, and may conveniently be of 55 welded steel construction. Its lower portion is affixed to a pair of brackets 20 and 21. These brackets are in turn secured to a suitable base 22. The main duct means M extends longitudinally through the interior of the tank T and, as shown in Figures 4 and 5, include an entrance

60 portion 24 disposed proximate the discharge of the blower B at one end of the tank T. The entrance portion 24 is generally rectangular in cross-section and merges into a pair of separate leg portions 28 and 30, the end of the entrance portion remote from the blower

65 B being defined by a generally V-shaped splitter element 31. These leg portions 28 and 30 are also generally 70

75

rectangular in cross-section. The leg portions are parallel and extend through one end wall 38 of the tank T, as shown in Figures 4 and 5. The return duct means R consist of a pair of identical diffuser members 32 and 34. The inlet end 36 of diffuser member 32 is affixed to the end of leg portion 28 remote from the blower B externally of the tank end wall 38, while the inlet end of the other diffuser member 34 is affixed to the same end of leg portion 30. The outlet ends 40 of the diffuser members are open and face the opposite external side surfaces of the tank T. It should be particularly noted that the combined vertical cross-sectional area of the two leg portions 28 and 30 is less than that of the entrance portion 24.

The blower B is of conventional centrifugal construction and includes a multi-bladed rotor 41 carried by a horizontal shaft 42. This shaft 42 is rotatably supported between a pair of aligned bearings 44 affixed to a framework 46. A shroud 47 encloses the rotor 41 and is affixed to the framework 46. This framework 46 includes a pair of parallel, horizontal rail elements 50 and 52. As shown in Figure 2, the rail elements 50 and 52 are each provided with a pair of longitudinally-spaced elongated slots 54. These slots 54 receive mounting bolts 56 which are attached to the opposite sides of the reservoir tank T so as to secure the rails 50 and 52 thereto. This arrangement permits longitudinal adjustment of the blower framework 46 towards and away from the end wall of the tank T for a purpose to be set forth hereinafter. It should be particularly noted that the discharge portion 58 of the blower shroud 47 is rectangular in configuration, and as indicated in Figures 4 and 5, it telescopically interfits within the entrance portion 24 of the main duct means M. A driven sheave 59 is keyed to one side of the rotor shaft 42, as is shown in Figures 2 and 4.

The pump P is also of conventional construction and in practice a gear pump has proven satisfactory. The lower portion of this pump P is affixed to a mounting bracket 60 welded to the upper portion of the reservoir tank T. The shaft 62 of the pump is keyed to a blower drive sheave 64. This blower drive sheave 64 is connected by a belt 66 to the driven sheave 59 that is keyed to the shaft 42 of the blower B. A second sheave 68 is keyed to the pump shaft 62 adjacent the aforementioned blower drive sheave 64. This latter sheave 68 is connected by a belt 70 to a driving sheave 72 that is keyed to the shaft of the electric motor E.

As shown in Figures 4, 5 and 6, the intake of the pump is in communication with the lower portion of the tank T by the inlet conduit 14. Preferably, the lower end of this inlet conduit 14 will be provided with a conventional filter 74. In practice, a wire mesh filter has proven satisfactory. The upper portion of the inlet conduit 14 extends through a cap 76 that is bolted to a cylindrical neck 78 formed on the upper portion of the tank T. A conventional oil breather 80 is also affixed to this cap 76. Referring now to Figure 1, the discharge of the pump P is connected to the pressure line 12. Preferably, a conventional check valve 82 will be interposed in this pressure line 12. Downstream of this check valve 82 a conventional pressure relief valve unit 84 is positioned. With this arrangement, should the pressure within the pressure line 12 rise above a pre-determined value, a portion of the hydraulic liquid flowing through the line will be returned to the interior of the tank T through a by-pass pipe 86.

As shown particularly in Figure 4, the end of the return line 16 adjacent the reservoir tank T includes a threaded fitting 88 centrally affixed to the upper portion of the tank end wall 36. The opposite end of this threaded fitting 88 is affixed to a discharge tube 90. This discharge tube 90 extends downwardly and longitudinally away from the tank end wall 38. The major portion of hydraulic liquid returned through the discharge

tube 90 follows the path indicated by the directional arrows in Figures 4 and 5. It should be observed that this path is counter to the direction of flow of the cooling air being forced through the main duct means M. To obtain such flow the interior of the tank T is provided with a horizontal floor 92 which interconnects the lower portion of the leg portions 28 and 30 of the main duct means M. One end of this floor is affixed to the tank end wall 38 while the other is bent upwardly adjacent the filter 74 so as to form an upstanding baffle 94. This baffle has a height corresponding to that of the leg portions 28 and 30 of the main duct means M. With this arrangement, the major portion of the returned hydraulic liquid discharged from the discharge tube 90 will tend to flow longitudinally relative to the reservoir tank T towards the blower end of the tank T between the facing sides of the leg portions 28 and 30 until it reaches the baffle 94. The presence of this baffle 94 will cause this hydraulic liquid to flow over the top of the baffle and also over the top of the leg portions 28 and 30, as indicated by the directional arrows in Figures 3, 4 and 6. Thereafter, this hydraulic liquid may enter the inlet conduit 14 by means of the filter 74.

In the operation of the aforescribed preferred embodiment of the present invention, rotation of the electric motor E will be transferred to the sheave 68 of the pump P by belt 70. Rotation of the sheave 68 will in turn effect concurrent rotation of the blower drive sheave 64. Rotation of this latter sheave 64 will be transferred to the driven sheave 59 of the blower B by the belt 66. As shown particularly in Figure 5, the pressurized air from the blower B will enter the entrance portion 24 of the main duct means M through the blower's discharge portion 58. Inasmuch as the combined vertical cross-sectional area of the leg portions 28 and 30 is less than that of the entrance portion 24, as noted hereinabove, the air flowing from the entrance portion into the leg portions will undergo an increase in velocity. Such increase in velocity will be proportional to the comparative vertical cross-sectional areas of these members. This increase in velocity of the air flowing to the leg portions 28 and 30 will serve to increase the rate of heat exchange through the walls defining the leg portions. After this high velocity cooling air has passed through the leg portions 28 and 30, it will flow through the diffuser members 32 and 34. These diffuser members will serve to reverse the direction of flow of this cooling air and direct it over the opposite external sides of the reservoir tank T. The diffuser members 32 and 34 should be so designed as to provide minimum diffusion of this air as it flows over the external surfaces of the reservoir tank. In this manner, a maximum heat exchange between the air and the hydraulic liquid within the reservoir tank will be attained.

The returned hydraulic liquid 10 will enter the reservoir tank T through the return line 16 and the attached discharge tube 90. Upon leaving the discharge tube 90 this liquid will flow away from the tank end wall 38 in a generally longitudinal direction relative to the reservoir tank T towards the blower end of the tank, as noted hereinbefore. Referring now to Figures 3 and 6, the volume of hydraulic liquid 10 within the reservoir tank should be so maintained that the level on the outer sides of the leg portions 28 and 30 is lower than the height of these leg portions and that of the baffle 94. With this arrangement, the hydraulic fluid contained between the facing surfaces of these leg portions, the tank end wall 38 and the baffle 94 will be forced to flow over the upper surfaces of the leg portions. An air breakout platform is thereby defined along the upper surfaces of the leg portions 28 and 30. In this regard, the film of hydraulic liquid overflowing the top surfaces of these leg portions is comparatively thin. As this hot hydraulic liquid comes into contact with the upper surfaces of the leg portions, the surface tension of the air bubbles entrained in the hydraulic liquid is increased because of

their reduction in volume resulting from the cooling action afforded by these upper surfaces. Accordingly, these air bubbles will burst and release their air into the space above the level of the hydraulic liquid. Thus, the cooled hydraulic liquid entering the intake of the pump P will not produce cavitation. The air released during the collapse of these air bubbles will leave the upper portion of the reservoir tank T by means of the oil breather 80.

As noted hereinabove, the longitudinal spacing of the blower B relative to the adjacent end of the reservoir tank T may be adjusted by means of the slots 54 and mounting bolts 56. During such longitudinal blower adjustment the shroud's discharge portion 58 will slide within the entrance portion 24 of the main duct means M. With this arrangement, it is possible to move the blower B towards and away from the splitter 31 until the static head affording maximum air delivery with minimum power expenditure is obtained. This longitudinal adjustment provision also makes it possible to adjust the tightness of the belt 66.

Referring now to Figures 7 and 8, there is shown a modified form of the heat exchanger apparatus embodying the present invention. This modified form is adapted for use where it is desired to heat the hydraulic liquid within the reservoir tank T rather than cool such liquid. In order to effect such heating, the blower B of the afore-described heat exchanger apparatus is merely enclosed within a two piece housing 100 having communication with a source of heated fluid, such as the interior of the hood 102 of an internal combustion engine 104. With this arrangement, as shown clearly in Figure 8, atmospheric air entering the interior of the hood 102 through its louvers 106 will be drawn over the external surface of the internal combustion engine 104 so as to be raised in temperature. This heated air will then be drawn through the housing 100 into the intake of the blower B. The blower B will force this air through the main duct means M and the return duct means R of the reservoir tank T in the manner described hereinabove so as to effect heating of the hydraulic liquid flowing therethrough. The housing 100 is formed of two telescopically interfitting sections 100a and 100b. This arrangement makes it possible to readily adjust the spacing between the engine 102 and the blower B to the space requirements of the installation. Preferably, the interior of both housing sections will be provided with a thermal insulating medium (not shown).

It will be apparent to those skilled in the art that various modifications and changes may be made with respect to the foregoing detailed description without departing from the spirit of the invention or the scope of the following claims.

I claim:

1. Heat exchanger apparatus, comprising: a liquid tank; main duct means extending through said tank in heat-transfer relationship with the liquid contents of said tank; blower means connected with the inlet end of said main duct means so as to urge fluid through the latter in a first direction; and return duct means in communication with the outlet end of said main duct means, said return duct means extending externally of said tank and being curved so as to direct said fluid over the exterior of said tank in a direction opposite to said first direction.

2. Heat exchanger apparatus, comprising: a liquid tank; main duct means extending through said tank, said main duct means including an entrance portion adjacent one end of said tank and a plurality of leg portions connecting said entrance portion with the opposite end of said tank; fluid-moving means connected with said main duct means so as to urge fluid through the latter; and return duct means including a plurality of diffuser members each being connected to one of said leg portions adjacent said opposite end of said tank and being curved so as to direct said fluid over the exterior of said tank.

3. Heat exchanger apparatus, comprising: a liquid tank; main duct means extending through said tank, said main duct means including an entrance portion adjacent one end of said tank and a plurality of leg portions connecting said entrance portion with the opposite end of said tank, the total cross-sectional area of said leg portions being less than that of said entrance portion; fluid-moving means connected with said main duct means so as to urge fluid through the latter; and return duct means including a plurality of diffuser members each being connected to one of said leg portions adjacent said opposite end of said tank and being curved so as to direct said fluid over the exterior of said tank.

4. Heat exchanger apparatus, comprising: a liquid tank; main duct means extending through said tank, said main duct means including an entrance portion adjacent one end of said tank and a plurality of leg portions connecting said entrance portion with the opposite end of said tank; fluid-moving means connected with the inlet end of said main duct means so as to urge fluid through the latter in a first direction; return duct means including a plurality of diffuser members each being connected to one of said leg portions adjacent said opposite end of said tank and being curved so as to direct said fluid over the exterior of said tank in a direction opposite to said first direction; means having an inlet proximate said entrance portion for removing liquid from said tank; and means having a discharge opposite said entrance portion for returning liquid to said tank, the major portion of said liquid flowing through said tank in the second direction.

5. Heat exchanger apparatus, comprising: a liquid tank; main duct means extending through said tank, said main duct means including an entrance portion adjacent one end of said tank and a plurality of leg portions connecting said entrance portion with the opposite end of said tank, the total cross-sectional area of said leg portions being less than that of said entrance portion; fluid-moving means connected with the inlet end of said main duct means so as to urge fluid through the latter in a first direction; return duct means including a plurality of diffuser members each being connected to one of said leg portions adjacent said opposite end of said tank and being curved so as to direct said fluid over the exterior of said tank in a direction opposite to said first direction; means having an inlet proximate said entrance portion for removing liquid from said tank; and means having a discharge opposite said entrance portion for returning liquid to said tank, the major portion of said liquid flowing through said tank in the second direction.

6. Heat exchanger apparatus, comprising: a liquid tank; main duct means extending through said tank in heat-transfer relationship with the liquid contents of said tank; blower means having a discharge in communication with the inlet of said main duct means so as to urge fluid through the latter; mounting means interposed between said tank and said blower, said mounting means permitting the spacing of said blower relative to the inlet of said main duct means to be varied; and return duct means in communication with said main duct means, said return duct means being curved so as to direct said fluid over the exterior of said tank.

7. Heat exchanger apparatus, comprising: a liquid tank; main duct means extending through said tank in heat-transfer relationship with the liquid contents of said tank; blower means having a discharge in communication with the inlet of said main duct means so as to urge fluid through the latter in a first direction; mounting means interposed between said tank and said blower, said mounting means permitting the spacing of said blower relative to the inlet of said main duct means to be varied; return duct means in communication with said main duct means, said return duct means being curved so as to direct said fluid over the exterior of said tank;

liquid removing means disposed proximate the inlet end of said main duct means; and means disposed at the end of said tank remote from the inlet end of said main duct for returning liquid to said tank means whereby the major portion of liquid will flow through a tank in said second direction opposite to said first direction.

8. Heat exchanger apparatus, comprising: a liquid tank; main duct means extending through said tank, said main duct means including an entrance portion adjacent one end of said tank and a plurality of leg portions connecting said entrance portion with the opposite end of said tank; blower means having a discharge in communication with said entrance portion so as to urge fluid through said main duct means in a first direction; mounting means interposed between said tank and said blower, said mounting means providing adjustment of the spacing between said entrance portion and the discharge of said blower; and return duct means including a plurality of diffuser members each being connected to one of said leg portions adjacent said opposite end of said tank and being curved so as to direct said fluid over the exterior of said tank in a second direction opposite to said first direction.

9. Heat exchanger apparatus, comprising: a liquid tank; main duct means extending through said tank, said main duct means including an entrance portion adjacent one end of said tank and a plurality of leg portions connecting said entrance portion with the opposite end of said tank, the total cross-sectional area of said leg portions being less than that of said entrance portion; blower means having a discharge in communication with said entrance portion so as to urge fluid through said main duct means in a first direction; mounting means interposed between said tank and said blower, said mounting means providing adjustment of the spacing between said entrance portion and the discharge of said blower; and return duct means including a plurality of diffuser members each being connected to one of said leg portions adjacent said opposite end of said tank and being curved so as to direct said fluid over the exterior of said tank in a second direction opposite to said first direction.

10. Heat exchanger apparatus, comprising: a liquid tank; main duct means extending through said tank, said main duct means including an entrance portion adjacent one end of said tank and a plurality of leg portions connecting said entrance portion with the opposite end of said tank; blower means having a discharge in communication with said entrance portion so as to urge fluid through said main duct means in a first direction; mounting means interposed between said tank and said blower, said mounting means providing adjustment of the spacing between said entrance portion and the discharge of said blower; return duct means including a plurality of diffuser members each being connected to one of said leg portions adjacent said opposite end of said tank and being curved so as to direct said fluid over the exterior of said tank in a direction opposite to said first direction; means having an inlet proximate said entrance portion for removing liquid from said tank; and means having a discharge opposite said entrance portion for returning liquid to said tank, the major portion of said liquid flowing through said tank in the second direction.

11. Heat exchanger apparatus, comprising: a liquid tank; main duct means extending through said tank, said main duct means including an entrance portion adjacent one end of said tank and a plurality of leg portions connecting said entrance portion with the opposite end of said tank, the total cross-sectional area of said leg portions being less than that of said entrance portion; blower means having a discharge in communication with said entrance portion so as to urge fluid through said main duct means in a first direction; mounting means interposed between said tank and said blower, said mounting means providing adjustment of the spacing between said entrance portion and the discharge of said blower; return duct

means including a plurality of diffuser members each being connected to one of said leg portions adjacent said opposite end of said tank and being curved so as to direct said fluid over the exterior of said tank in a direction opposite to said first direction; means having an inlet proximate said entrance portion for removing liquid from said tank; and means having a discharge opposite said entrance portion for returning liquid to said tank, the major portion of said liquid flowing through said tank in the second direction.

12. Heat exchanger apparatus, comprising: a horizontally extending liquid tank; main duct means extending through said tank, said main duct means including an entrance portion adjacent one end of said tank and a pair of leg portions connecting said entrance portion with the opposite end of said tank; blower means having a discharge in communication with said entrance portion so as to urge fluid therethrough in a first direction; return duct means including a pair of diffuser members, each being connected to one of said leg portions adjacent said opposite end of said tank and being curved so as to direct said fluid over the opposite external sides of said tank in a second direction opposite to said first direction; a floor interconnecting the lower portions of said leg portions, said floor terminating at a point remote from said opposite end of said tank; an upstanding baffle on said floor at its point of termination and having a height approximately that of said leg portions; liquid withdrawal means in said tank adjacent said entrance portion; and liquid return means including a discharge nozzle between said leg portions adjacent said opposite end of said tank and extending away from said opposite end so as to direct the major portion of liquid carried thereby in said second direction.

13. Heat exchanger apparatus as set forth in claim 12 wherein the combined vertical cross-sectional area of the leg portions of said main duct means is less than that of the entrance portion thereof.

14. Heat exchanger apparatus, comprising: a horizontally extending liquid tank; main duct means extending through said tank, said main duct means including an entrance portion adjacent one end of said tank and a pair of leg portions connecting said entrance portion with the opposite end of said tank; blower means having a discharge in communication with said entrance portion so as to urge fluid through said main duct means in a first direction; mounting means interposed between said tank and said blower, said mounting means providing adjustment of the spacing between said entrance portion and the discharge of said blower; return duct means including a pair of diffuser members, each being connected to one of said leg portions adjacent said opposite end of said tank and being curved so as to direct said fluid over the opposite external sides of said tank in a second direction opposite to said first direction; a floor interconnecting the lower portions of said leg portions, said floor terminating at a point remote from said opposite end of said tank; an upstanding baffle on said floor at its point of termination and having a height approximately that of said leg portions; liquid withdrawal means in said tank adjacent said entrance portion; and liquid return means including a discharge nozzle between said leg portions adjacent said opposite end of said tank and extending away from said opposite end so as to direct the major portion of liquid carried thereby in said second direction.

15. Heat exchanger apparatus as set forth in claim 14 wherein the combined vertical cross-sectional area of the leg portions of said main duct means is less than that of the entrance portion thereof.

16. Heat exchanger apparatus, comprising: a liquid tank; main air duct means extending through said tank, said main air duct means including an entrance portion adjacent one end of said tank and a plurality of leg portions connecting said entrance portion with the opposite end of said tank; a blower connected with said main air duct means so as to urge air through the latter; and return

air duct means including a plurality of diffuser members each being connected to one of said leg portions adjacent said opposite end of said tank and being curved so as to direct said air over the exterior of said tank.

17. Heat exchanger apparatus, comprising: a liquid tank; main air duct means extending through said tank, said main air duct means including an entrance portion adjacent one end of said tank and a plurality of leg portions connecting said entrance portion with the opposite end of said tank, the total cross-sectional area of said leg portions being less than that of said entrance portion; a blower connected with said main air duct means so as to urge air through the latter; and return air duct means including a plurality of diffuser members each being connected to one of said leg portions adjacent said opposite end of said tank and being curved so as to direct said air over the exterior of said tank.

18. Heat exchanger apparatus, comprising: a liquid tank; main air duct means extending through said tank, said main air duct means including an entrance portion adjacent one end of said tank and a plurality of leg portions connecting said entrance portion with the opposite end of said tank; a blower connected with the inlet end of said main air duct means so as to urge air through the latter in a first direction; return air duct means including a plurality of diffuser members each being connected to one of said leg portions adjacent said opposite end of said tank and being curved so as to direct said air over the exterior of said tank in a direction opposite to said first direction; means having an inlet proximate 30 said entrance portion for removing liquid from said tank;

and means having a discharge opposite said entrance portion for returning liquid to said tank, the major portion of said liquid flowing through said tank in the second direction.

5 19. Heat exchanger apparatus, comprising: a liquid tank; main air duct means extending through said tank, said main air duct means including an entrance portion adjacent one end of said tank and a plurality of leg portions connecting said entrance portion with the opposite 10 end of said tank, the total cross-sectional area of said leg portions being less than that of said entrance portion; a blower connected with the inlet end of said main air duct means so as to urge air through the latter in a first direction; return air duct means including a plurality of diffuser members each being connected to one of said leg portions adjacent said opposite end of said tank and being curved so as to direct said air over the exterior of said tank in a direction opposite to said first direction; means having an inlet proximate said entrance portion for removing liquid from said tank; and means having a discharge opposite said entrance portion for returning liquid to said tank, the major portion of said liquid flowing through said tank in the second direction.
